UNITED STATES PATENT OFFICE.

FRANK J. LEWIS AND LEO B. BROWN, OF HUNTSVILLE, ALABAMA.

CONVERTIBLE FURNITURE.

Application filed March 21, 1922. Serial No. 545,418.

To all whom it may concern:

Be it known that we, FRANK J. LEWIS and LEO B. BROWN, citizens of the United States, residing at Huntsville, in the county of 5 Madison and State of Alabama, have invented certain new and useful Improvements in Convertible Furniture, of which the following is a specification.

Our invention relates to convertible furniture and the object of the invention is to 10 provide a piece of furniture of this class that combines the characteristics of an ironing board and a step ladder.

In the accompanying drawings, one embodiment of the invention is illustrated, and

Figure 1 is a perspective view of the device erected as an ironing board;

Figure 2 is a fragmentary longitudinal section of Figure 1 illustrating the securing 20 means between the ironing board and one of its supports;

Figure 3 is a similar view of the securing means at the other end of the board, the section being taken on the line 3—3 of 25 Figure 1.

The block 12 is supported on four legs 13 and is provided with a central bore adapted to receive the perpendicular post 15 which fits snugly therein and is adjustable in its 30 length direction by means of a pin 16 engaging in one of the transverse apertures 17 provided along the lower end of the post. The block 12 is preferably provided with a recess 18 in which the pin 16 may rest.

The ironing board consists of the usual board 27 with a socket member 28 secured at one end thereof and adapted to engage the upper end of the post 15. At the other end of the board 27 is hinged, as at 29, a jaw 40 30 protruding upwardly through a slit 31 in the board. The lower end of the jaw 30 is extended downwardly terminating with a shank 32 which is long enough to rest on the floor. The support of this end of the ironing board consists of a ladder 33 provided with a number of rungs or steps 34 with any one of which the end of the board 27 may engage in the manner indicated in Figures 1 and 2. That is to say, the jaw 30 reaches above one of the rungs 34 and the

extended fingers 35 engage with the under side of the same rung and in this manner provide a good grip on the ladder. In order to more securely connect the ironing board with the ladder, a brace 36 is provided which at one end 37 hooks over another of the rungs on the ladder 33 and at its other end is pivoted, as at 38, to the shank 32 of the jaw member. A number of apertures 39 are provided along the brace 36 for close adjustment.

The ladder 33 is in the usual manner provided with a pair of legs 40 hinged to the ladder, as at 41. A brace 42 connects the two legs and a snap latch 43 holds the legs closed up to the ladder when the latter functions as a support for the ironing board or when it is put away. A bracket 44 is secured to the top of the ladder and serves as a stand for the flat iron.

Having thus described the invention, what is claimed as new is:

1. An ironing-board having a top and a support therefor; said support comprising a ladder-shaped member provided with 75 rungs, a gripping member journaled on the under side of said top and extending through the same, adapted to hold one of said rungs tightly against one end of said top, said gripping member having a downwardly extending shank, a link having detachable engagement with said shank and with another of said rungs for locking said gripping member, and a vertically extensible stand for the other end of said top. 80

2. An ironing-board having a top and supports therefor; one of said supports comprising a socket on the under side of said top, a stand having a vertical opening therethrough and a seat in its upper side 90 communicating with said opening, a post engaging in said opening and in said socket and provided with a plurality of diametric apertures, and a holding member engaged through any one of the said openings and 95 resting in the seat in the stand.

In testimony whereof we affix our signatures.

FRANK LEWIS. [L.S.]
LEO B. BROWN. [L.S.]
